Primary Examiner — Eric Goodman*Assistant Examiner* — Sloan Rozin(74) *Attorney, Agent, or Firm* — Merchant & Gould P.C.(57) **CLAIM**

The ornamental design for a contact lens case, as shown and described.

DESCRIPTION

FIG. 1 is a perspective view of a contact lens case, according to our design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

In the above drawings, the broken lines and the areas within the broken lines form no part of the claimed design.

1 Claim, 5 Drawing Sheets(56)
